UNITED STATES PATENT OFFICE

JESSE C. MARTIN, JR., OF LOS ANGELES, CALIFORNIA

SELF-SUPPORTING WATER-BOTTOM STRUCTURE

Application filed August 21, 1928. Serial No. 301,123.

The invention relates to water bottoms and has as an object the provision of water bottom units combined with a structure which holds the units in correct spacing and makes the entire structure self-supporting.

It is a further object of the invention to provide a water bottom structure having means connecting the lower inner edges of the units so as to produce an air-tight housing about the same and in combination with the units themselves to make the entire structure self-supporting and capable of supporting the refractory elements covering the surfaces thereof not contacted by water.

It is a further object of the invention to provide a water bottom structure formed in separate units for convenience of insertion into existing locomotives without removing the boiler from the frame, and having elements secured to the units whereby the units and elements form a single self-supporting structure.

Further objects of the invention will appear from the following description when read in connection with the accompanying drawings showing an illustrative embodiment of the invention and wherein:

Fig. 1 is a plan view of the structure of the invention showing the water legs of the firebox in cross section;

Fig. 2 is a central vertical section on line 2-2 of Fig. 1;

Fig. 3 is a detail vertical transverse section on line 3-3 of Fig. 1;

Fig. 4 is a perspective view of a spacing element;

Fig. 5 is a vertical transverse section on broken line 5-5 of Fig. 1; and

Fig. 6 is a detail view partly in vertical longitudinal section of a blow-off connection.

The invention is shown as applied to the firebox of a locomotive boiler wherein the side water legs are shown at 10, 11, the rear water leg at 12, and the front water leg at 13, said water legs terminating downwardly in a mud ring 14 in the usual manner.

The device comprises a pair of spaced water bottoms of the character described and claimed in my Patent No. 1,663,806, dated March 27, 1928, indicated at 15, 16, which are

formed at their lower edges with tubular members 17, 18 spaced apart, the space thus provided being filled in with refractory material 119. The elements 15, 16 are freely open at their outer edges and the upper walls of the units merge into the side sheets of the water legs while the lower walls are turned downwardly and as shown are secured to the mud ring.

In the form shown in my patent referred to the water bottom structure is supported by slings passing beneath the same which may be secured to the mud ring or the supporting frame of the boiler. According to the present invention a structure is provided which will be self-supporting and in which the slings referred to will be unnecessary. To this end and to hold the lower edges of the units properly spaced, members 19, 20 are provided one of which is shown in perspective in Fig. 4. As there shown the members present an angular conformation having vertical web 21 and a horizontal web 22.

The ends of members 19, 20 are cut away to provide arcuate recesses 23, 24 and the portions 25, 26 at the upper side of the recesses are beveled to seat against the rounded end walls of the units in the manner illustrated in Fig. 3. Also the ends 27, 28 of web 22 are shown as beveled to seat against the rounded surface of the tubular members 17, 18.

In addition, a lug 29, 30 is provided in the bottom of each recess 23, 24 to contact with the tubular member 17, 18 and to secure an accurate spacing of these lugs during assembly. After the spacing members are in place and in firm contact with the units 15, 16, the ends 25, 26, 27, 28 thereof are welded to the units and the surface of the recesses 23, 24 are also welded, the welding material being used to fill in about the lugs 29, 30 so as to make the entire joint air-tight.

A bottom plate 31 is shown which is riveted to the web 22 of the spacing members 19, 20, the margins 32 of the plate 31 being turned to lap upon the cylindrical portions 17, 18 of units 15, 16 as clearly illustrated in Fig. 3, said margins being welded to the units. The plate 31 serves as a connection between the water bottom units completing an inverted

truss therewith, forms an air-tight closure for the space between the units and supports the refractory filling 119.

Transverse plates 33, 34 are shown riveted to the web 21 of spacing members 19, 20, the ends of the plates being secured by angles to the inside side sheets of the boiler and upon said plates angles 35, 36 are secured to support horizontal plates 37, 38 upon which brick work to complete the enclosure of the firebox is supported.

A flash wall 39 is shown supported upon the spacing member 19 and upon the bottom refractory material 119 and burner wall 40 is likewise supported by the spacing member 20 and upon the refractory material 119 having an opening therein for a fluid fuel burner 41.

Fire brick or other form of refractory is provided at 42, 43 to complete the protection of the housing.

Angles 44, 45 are shown riveted to the plates 33, 34 supported by the plates 46 in spaced relation from the lower surfaces of the units, the spacing being preserved as shown in Fig. 5 by means of studs 47, 48. The space thus provided may be filled in with heat insulating material as metal wool or asbestos. An air inlet is shown at 49 through the plate 31 to admit air into the firebox for combustion.

A positive connection between the units and the members 19, 20 and the units of the water bottom is shown in the form of a collar 60 surrounding the ends of the portions 17, 18 of the units adjacent the flanged connections formed on the ends thereof, each collar having a lug 61 projecting therefrom which is secured to the members 19, 20 as by rivets 62. By virtue of the collar and lug connection 60, 61 and the spacing members 19, 20, the units are prevented from sagging, nor can one of them alone sag, and therefore the plate 31 is at all times held level. Also by virtue of these collars and the lugs 29, 30 on members 19, 20, the assembly of the device is very greatly simplified as the parts are firmly held substantially in correct position while the joints are being welded.

To introduce water into the units from the barrel of the boiler, according to the form of the invention shown for purposes of illustration, conduits 50, 51 are shown having flange connections at 52, 53 with the cylindrical portions 17, 18 of the units and by means of flange connections 54, 55 with the inside throat of the front water leg.

It will be understood that in lieu of the connections shown at 50, 51, inlets for water to the units may be placed into communication with the side water legs in advance of the units or with the bottom of the boiler as shown for purposes of illustration in my patent above referred to, or be omitted altogether and circulation in the units may take place

into and out of the side water legs themselves.

To enable sediment to be blown off from the tubular members 17, 18 of the units, there are shown blow-off connections 56, 57, one of which is shown in detail, Fig. 6, comprising a flange 58 for connection to a member 17 or 18, a flange joint 59 whereby the two elements 56, 57 may be secured together and a flange joint 60' to which a blow-off conduit may be secured. By provision of the inter-communicating blow-off connection shown the units may both be blown off from either side of the boiler.

By the structure described, or mechanical equivalents thereof, a water bottom structure is provided which is amply self-supporting. As a measure of precaution slings may be installed but where such slings are interfered with by the springs, wheels or frame of the locomotive, they may be omitted as shown and the structure is amply strong to resist all strains in use or during repair of the inside of the firebox.

Minor changes may be made in the physical embodiment of the invention within the scope of the appended claims without departing from the spirit thereof.

I claim:

1. A self-supporting water bottom structure comprising, in combination, separate water bottom units, means to hold said units in properly spaced relation in a firebox, certain of said means welded to said units and forming therewith a unitary structure which is self-supporting between the side water legs of the firebox.

2. A self-supporting water bottom structure comprising, in combination, separate water bottom units, means to hold said water bottom units spaced apart in a firebox, means to hold said units against said spacing means, said first named means welded to said units and both of said means forming with said units a complete structure which is self-supporting between the side water legs of the firebox.

3. A self-supporting water bottom structure comprising, in combination, separate water bottom units secured to the side water legs of the firebox and in circulatory communication therewith, spacing means located between the inner edges of said units at the ends thereof to hold said units in properly spaced relation and welded thereto, means secured to said spacing means and contacting said units to prevent separation thereof, and a bottom sheet secured to said spacing means having its side margins welded to said units and forming an air tight closure for the space therebetween, whereby to form a water bottom structure which is self-supporting between the side water legs of the firebox.

4. A self-supporting water bottom structure comprising, in combination, separate

water bottom units secured to the side water legs of a firebox and in circulatory communication therewith, said units terminating inwardly in substantially tubular portions projecting at their ends beyond the ends of the units, spacing members extending between said units contacting said tubular portions and welded thereto, a collar surrounding each projecting end of said units and each having a portion projecting into contact with said spacing means and secured thereto and a bottom plate having its side margins welded to said tubular portions and its end margins secured to said spacing means to provide a complete water bottom structure which is self-supporting between said water legs.

5 5. A self-supporting water bottom structure comprising, in combination, separate water bottom units, one connected to each of 10 of the side water legs of a firebox and in circulatory communication therewith, said units spaced apart at their inner edges, said units terminating inwardly in substantially tubular portions, spacing means for said units 15 having arcuate recesses at their ends to conform to the surface of said tubular portions and welded thereto, said spacing means each comprising a vertical and a horizontal web, a collar surrounding a projection of said 20 tubular portion at each end of each of said units, said collars having portions projecting into contact with said vertical webs and secured thereto, a bottom plate secured to said 25 horizontal webs at their ends and welded to 30 said tubular portions at its side margins, a lining of refractory material between said units carried by said plate whereby a water bottom structure is provided which is self-supporting between said side water legs.

35 6. A self-supporting water bottom structure comprising, in combination, separate water bottom units, each unit secured to the side water legs of a firebox and in circulatory communication therewith and terminating 40 inwardly in spaced-apart tubular portions projecting at their ends beyond the ends of said units, a spacing member at each end of the space between said units comprising vertical webs shaped to conform to the 45 surface of said tubular portions and the adjacent portions of the ends of the units and welded thereto and comprising also a horizontal web, a bottom plate secured at its 50 ends to said horizontal webs and having its side margins in contact with and welded to the surface of the said tubular portions, vertical housing plates secured at their lower margins to said vertical webs and horizontal housing plates secured to said vertical plates 55 60 to complete the enclosure of the bottom of the firebox and a refractory lining supported upon said bottom plate and said horizontal housing plates to protect the structure of said firebox not contacted by water.

65 7. A water bottom structure comprising

spaced water bottom units, each unit in circulatory communication with one of the side water legs of a firebox, the ends of said units provided with blow-off connections having portions projecting into communication with each other and means to connect a blow-off cock with each of said blow-off connections, whereby both of said units may be simultaneously blown off from either side of the boiler.
